BENJAMIN F. MIESSNER, OF SHORT HILLS, NEW JERSEY, ASSIGNOR TO MIESSNER INVENTIONS INC., OF SHORT HILLS, NEW JERSEY, A CORPORATION OF NEW JERSEY

ELECTROMAGNETIC SOUND REPRODUCER

Application filed August 24, 1929. Serial No. 388,131.

The present invention relates to electro-magnetic sound reproducers, and more particularly to those reproducers including provision for maintaining therein an intense magnetic field.

The invention contemplates in particular the so-called electrodynamic type of sound reproducer in which an intense magnetic field is maintained for interaction with a dynamic coil excited with the sound representing currents.

An object of the invention is the provision of an arrangement whereby the field producing coil of such a reproducer can be excited with a uni-directional pulsating current without disturbing effects on the dynamic coil, and in particular excited with incompletely filtered rectified alternating current, as is had in the now usual practice of energizing the three-electrode vacuum tubes of amplifying systems from commercial alternating current sources.

In the usual mode of construction of electrodynamic reproducers as so-called loud speakers for radio broadcast receivers and electrical phonographs the field coil is made of such electrical dimensions that its inductive impedance is of suitable value as to be well adapted to function as the high inductive impedance in a filter system associated with an alternating current rectifier for supplying the plate and grid energy for amplifier tubes. Such use eliminates the usual choke coil, or one coil if two or more are employed, of such filter systems, thereby saving weight, space and cost of material. However, the incompletely filtered current at the point in a filter system where the field coil must be used in order to replace a choke coil makes for a severely fluctuating field for the dynamic coil of the speaker, with the effect that the resulting hum has heretofore proven undesirably intense.

In my application Serial Number 344,941, filed March 7, 1929, of which this application is a continuation in part, I disclosed several forms of dynamic speakers designed for operation under predetermined conditions with means for neutralizing any hum effects when

the field coil thereof was excited by a source of fluctuating uni-directional current.

I have found that when such a speaker was operated under conditions very abnormal to the conditions for which it was designed 55 slightly audible hum developed therein. It is therefore the purpose of this invention to provide an electrodynamic speaker, the hum neutralization effects within the speaker being variable to adapt the same to widely varying conditions of use and field coil excitation.

My invention will be readily understood from the following description in connection with the accompanying drawings in which 65

Fig. 1 shows in a cross sectional view the usual form of construction of so-called dynamic speakers arranged to include features of my present invention; and

Fig. 2 diagrammatically illustrates suitable electrical connections for taking advantage of the features of Fig. 1.

Referring to Fig. 1, a magnetic circuit of the usual form of electrodynamic reproducer is shown to include a cylindrical element 1 of cast iron or other magnetic material having a closure at one end by an integral part of the casing, and a closure at the other end comprising a disk 4 of soft iron or other suitable magnetic material secured 75 to the wall of the cylinder 1 by means of a suitable series of screws 9. A central core 2 of soft iron or other suitable magnetic material is bolted to the base of the cylindrical element 1 by a bolt 3 as shown, the core 2 extending through a circular opening in the front disc 4 as shown, the opening in the disc 4 being of slightly larger diameter than the diameter of the core 2 in order to accommodate a coil 6 secured to a cylindrical projection 7' of a conical sound producing element 7.

A coil 5, usually comprising many turns of fine wire, encircles the core 2, and is arranged with input terminals 13 and 14 through which the field producing or energizing current is supplied. This coil I have wound upon a spool *a*, the bore of which preferably snugly fits the core 2 with only sufficient clearance to be moved therewith when pressure is exert- 100

ed upon the coil. Around the coil 5 I have provided a clamping ring *b*, having a pressure member *c* extending through an aperture *d* in the casing 1. Upon the casing 1 adjacent the aperture *d* I have provided two lugs *e*, *e'* provided with threaded adjustment screws *f*, *f'*, the axes of which are parallel to the axis of the coil 5 and the pressure tips of which engage the member *c*. It is to be understood that other means may be provided for adjusting the coil 5 longitudinally of the core 2 without departing from the spirit of my invention, the particular structure shown being merely by way of illustration.

15 With the arrangement shown, the energizing of the coil 5 with a uni-directional current produces a magnetic flux which in major part takes a path through the core 2, the gap between the end of the core 2 and the surface of the opening in the disc 4, through the body of the disc 4 to the walls of the cylindrical element 1, and thence through the base of the cylindrical element 1 to the core 2 to complete the magnetic circuit.

25 The magnetic flux is thus concentrated in the annular gap between the end of the core 2 and the opening in the disc 4, the two sides of the gap being marked N and S to indicate magnetic polarities, but these polarities can be reversed from those indicated without altering the mode of operation. The coil 6 is so mounted on the cylindrical extension 7' in the gap as to be movable therein, and preferably without interfering contacts with the gap portions, so that when sound representing currents are applied to this coil through the terminals 15 and 16, there is a motion producing reaction set up between the coil and the intense magnetic field of the gap, resulting in sound reproducing motion being imparted to the cone 7 or other associated sound reproducing element. The usual construction of electrodynamic reproducer endeavors to make the air gap as short as the structure of the coil 6 and its mounting on the cylindrical element 7' will permit while leaving sufficient clearance to prevent frictional contacts, this in order that the flux in the gap may be maintained as intense as possible for a given structure of magnetic system and field producing coil.

35 If the coil 5 is energized from a source, such as rectified and filtered alternating current having a pulsating component, obviously the resulting flux through the gap will be of unidirectional pulsating character, and will react with the coil 6, with or without the signal representing current flow, to produce motion of the cone 7 that will cause a hum characteristic of the pulsations in the field exciting current, an undesirable feature in sound reproducing devices in general, particularly those used for entertainment purposes such as phonographic reproduction or radio broadcast reception.

Because of convenience, the distaste of the public for batteries and the characteristics of the electrical energy required, it is almost compulsory to employ energy derived from commercial alternating current sources for energizing the field coil of current designs of electrodynamic reproducers. Further, the high inductance available in the field coil of commercial electrodynamic reproducers makes these coils particularly suitable as the inductive impedance element of the filter systems commonly used in connection with filtering rectifier alternating current for energizing the plate and grid electrodes of three-electrode vacuum tube amplifiers used in radio receivers and electrical phonograph reproducers, and such use saves the expense, weight and space of additional coils for filter purposes in addition to avoiding the employment of a separate source of current for energizing the field coil. In addition, the users of such devices, apparently unconcerned about the electrical design thereof, substitute one speaker system for another without regard to the conditions to which such a system is to be subjected.

45 For these reasons a satisfactory arrangement for preventing the production of hum when energizing the field coil with uni-directional current having widely varying direct current and fluctuating current components is of great importance, and the features of my present invention permit this hum elimination to be accomplished in a most effective degree by simple adjustments.

55 In my application hereinbefore referred to I described the action of a "bucking coil" placed at points within the magnetic system and found that it was necessary to govern the magnetic induction in the bucking coil both as to intensity and wave form to bring about most complete neutralization of hum effects. These principles apply equally to the location of the "bucking coil" of my present invention and I have found that by varying these effects differentially with the differential variations in the armature coil under widely varying conditions of energization of the field coil, I can maintain the satisfactory low hum characteristics of the speaker throughout very wide ranges of operating conditions.

65 In Fig. 1, I have shown a magnetic circuit employing the features described with reference to Fig. 1 of my copending application, and have found that by locating the bucking coil 8, of a pan-cake form and having terminals 17 and 18, at the base of the core 2, and held in position closely adjacent the casing 1 by a small press-fit ring 8a, the potentials developed at the terminals 17, 18 can be varied throughout a wide range of values by the adjustment of the coil 5 along the core 2 by means of the screws *f*, *f'*. I have also found that these potentials vary differentially with

respect to the varying potentials developed upon the terminals 15, 16 of the coil 6.

Considering the circuit arrangement of Fig. 2, the core 2 of Fig. 1 is shown with field coil 5 connected to be energized by way of terminals 13 and 14, as from a source 26 of periodically fluctuating uni-directional current. Dynamic coil 6 is shown connected to be supplied with sound representing currents through a transformer OT connected to, for example, the output terminals 21 and 22 of an amplifier system. The coil 6 is connected in series with coil 8 through a potentiometer 24 across the terminals 17 and 18, or other suitable means, permitting adjusting the magnitudes of the hum bucking current collected in coil 8 applied to coil 6, a control equivalent to the control arrangement described with reference to Fig. 2 of my pending application.

As a practical procedure the coil 8 may be constructed with more turns than needed for neutralizing for a normal position of coil 6, and the potentiometer used for securing an adjustment for taking care of production discrepancies in location of coil 6. Or the potentiometer adjustment may be utilized for correcting for residual hum current coming from a preceding amplifier.

30 With a design of coil 8 to effect neutralization under a given set of conditions the potentiometer 24 may be dispensed with, the coil 6 being directly connected across the terminals 17, 18 through the secondary 16 of the transformer OT.

When the speaker system is to be operated under conditions widely differing from those for which it was originally set, hum neutralization may be again established by varying 40 the position of the coil 5 relative to the coils 6 and 8 as indicated by the arrow.

While I have disclosed my invention with particularity with respect to specific embodiments thereof, no limitations by reason of such choice for explanatory purposes are intended, the invention being one of broad scope capable of numerous adaptations readily apparent to those skilled in the art.

Having fully described my invention, I claim:

1. In an electromagnetic sound reproducer, the combination of a magnet energized by direct current, an air gap in the magnetic circuit of said magnet, a dynamic coil adapted to be energized with sound representing currents operatively located in said air gap, and means for eliminating disturbances in said dynamic coil due to periodic fluctuations of said direct current comprising a second coil coupled to said magnet connected in opposing series with said dynamic coil and dynamically independent thereof, and means for adjustably differentially apportioning the relative intensity of magnetic induction within said two coils.

65 2. In an electromagnetic sound reproducer,

the combination of an electromagnet comprising a core and a solenoid thereon adapted to be energized with fluctuating unidirectional current, said core constituting a magnetic circuit having a gap therein, a dynamic coil adapted to be energized with sound representing currents operatively located in said air gap, means for eliminating disturbances in said dynamic coil due to the fluctuations of said uni-directional current comprising a second coil connected in opposing series with said dynamic coil and dynamically independent thereof, and means for adjustably varying and apportioning the relative induction between said solenoid and each of said coils.

3. In an electromagnetic sound reproducer, the combination of an electromagnet comprising a core and a solenoid thereon adapted to be energized with fluctuating unidirectional current, said core constituting a magnetic circuit having a gap therein, a dynamic coil adapted to be energized with sound representing currents operatively located in said air gap, means for eliminating disturbances in said dynamic coil due to the fluctuations of said uni-directional current comprising a second coil connected in opposing series with said dynamic coil and dynamically independent thereof, said coils being located at opposite ends of said solenoid, and means for adjustably varying and apportioning the relative induction between said solenoid and each of said coils.

4. In an electromagnetic sound reproducer, the combination of an electromagnet comprising a core and a solenoid thereon adapted to be energized with fluctuating unidirectional current, said core constituting a magnetic circuit having a gap therein, a dynamic coil adapted to be energized with sound representing currents operatively located in said air gap, means for eliminating disturbances in said dynamic coil due to the fluctuations of said uni-directional current comprising a second coil connected in opposing series with said dynamic coil and dynamically independent thereof, said coils being located at opposite ends of said solenoid and substantially co-axial therewith, and means for adjustably varying and apportioning the relative induction between said solenoid and each of said coils.

5. In an electromagnetic sound reproducer, the combination of a magnetic system having a gap therein, a solenoid surrounding a portion of said magnetic system for producing a magnetic flux across said gap, said gap and said solenoid being substantially co-axial, a dynamic coil within said gap, a second coil electrically connected in opposing series with said dynamic coil and co-axially mounted at one end of said solenoid at an appreciable distance therefrom, and means for varying the relative position of said solenoid between said two coils for the elimination of displace-

ment of said dynamic coil by variations in the flux of said solenoid.

6. In an electromagnetic sound reproducer, the combination of a magnetic system having a gap therein, a solenoid surrounding a portion of said magnetic system for producing a magnetic flux across said gap, a dynamic coil mounted within said gap substantially coaxial with said solenoid, a second coil electrically connected in opposing series with said dynamic coil and co-axially mounted at one end of said solenoid at an appreciable distance therefrom, and means for varying the relative position of said solenoid between said two coils for the elimination of displacement of said dynamic coil by variations in the flux of said solenoid.

7. In an electromagnetic translating device including a magnetic field having a fluctuating component and a movable coil adapted to be energized by signal currents and linked with flux of said magnetic field, the combination of an auxiliary coil having a flux interlinkage with said magnetic field of substantially like harmonic composition as that in said movable coil, connections for opposing the fluctuating energy components transferred from said magnetic field to both of said coils, and means for adjustably differentially apportioning said transferred energy components.

In witness whereof, I have hereunto subscribed my name this 23rd day of August, 1929.

35 BENJAMIN F. MIESSNER.
